FOUNTAIN COMB

Filed May 18, 1932

UNITED STATES PATENT OFFICE

ROSE W. STARR, OF CHICAGO, ILLINOIS

FOUNTAIN COMB

Application filed May 18, 1932. Serial No. 611,954.

This invention relates to a fountain comb and will be described as incorporated in a comb adapted to be carried in a lady's purse.

An object of this invention is the provision 5 of a comb incorporating means for supplying liquid to the hair to moisten the same when being combed and being suitable for carrying in a lady's purse without the escape of liquid.

10 A further object of this invention is the provision of a comb of the type identified which is adapted to distribute fluid from substantially the entire length thereof, but which is also adapted to be used in such a manner 15 that liquid may be distributed from only one end thereof or any desired portion thereof without having liquid distributed from other portions.

20 A further object of this invention is the provision of an improved liquid containing sack so designed and constructed that certain portions thereof are automatically sealed from other portions thereof so that fluid may be contained in one portion without escaping 25 to another portion.

A further object of this invention is the provision of capillary means associated with 30 said fluid containing sack, adapted for the application of fluid from the sack directly to the hair being combed without the necessity of first distributing the fluid to the surface of the teeth.

A still further object of this invention is the provision of an improved shield for the 35 teeth of the comb to guard the same when not in use and to reduce the likelihood of liquid escaping from the sack and moistening the contents of a purse in which it may be carried.

40 Other objects and advantages of this invention will become apparent from the following detailed description with reference to the accompanying drawing.

On the drawing:

45 Figure 1 is a side elevation of a comb with a portion of the shield broken away and illustrating my invention.

Figure 2 is an elevational view of an end 50 of that shown in Figure 1.

Figure 3 is a longitudinal section taken

substantially on a central vertical plane through the device shown in Figure 1, with the shield removed.

Figure 4 is a cross vertical section taken on substantially the line IV—IV of Figure 3. 55

Figure 5 is a longitudinal horizontal section through a fragment of that shown in Figure 3 and taken on substantially the line V—V of Figure 3.

Figure 6 is a vertical cross-section similar 60 to Figure 4 but taken through a modified form of my invention.

As shown on the drawing:

The device shown in the drawing for illustrating my invention comprises a comb including a substantially cylindrical body portion 5 having formed integrally therewith a multiplicity of longitudinally spaced teeth 6. The battery portion 5 is provided with a longitudinally extending cavity 7 being substantially cylindrical with a flattened portion at the top providing a seat 8 against which the metal plate 10 is adapted to be pressed by the self-sustaining resiliency of the liquid containing sack 9 disposed in the cavity 7 and adapted to be deflated by downward pressure on the metal plate 10. 65 70 75

Means for exerting a downward pressure on the metal plate 10 is provided which comprises a lever 11 disposed in a recess in the top of the comb body and pivoted thereto by a pin 12 in such a manner that when the end 13 is lifted the end 14 is depressed, forcing downwardly on the plate 10. 80

The sack 9 is preferably composed of a plurality of longitudinally arranged cells 15 which are hermetically sealed from each other, by cementing or vulcanizing together opposite sides of the sack at longitudinally spaced intervals as indicated at 16. A plurality of depending nipples 17 are formed integrally with the sack 9, there being at least one nipple for each cell 15 to provide a passageway through which liquid may be drawn into the individual cells of the sack, and through which liquid may be distributed or fed to the surface of the teeth 6 or directly to the surface of the hair being combed for moistening the same. One important feature 90 95 100 of this invention is the provision of the nip-

plies 17 with a substantially capillary opening or duct therethrough as indicated at 21 through which liquid may be drawn by direct contact with the hair being combed. As best illustrated in Figure 4, the lower end of the nipple 17 extends slightly below the upper end of the teeth 6 in order that the nipple may directly engage the hair when being combed.

One end of the body 5 is provided with an opening through which the sack 9 may be inserted, and this opening is preferably closed by a suitable plug 23 as shown in Figure 3.

In order that the comb may be readily carried in a lady's purse or in a pocket, a shield 25 is provided which consists of a sheet of metal or other suitable material folded upon itself and having at its upper end inwardly disposed beads or corrugations 27 for engaging in longitudinal recesses 28 along the sides 20 of the comb adjacent the upper ends of the teeth, for holding the shield in place as indicated in Figure 2. The shield 25 is preferably closed at one end to facilitate the retention of the shield in place. For removing or 25 placing the shield on the comb, it is preferably moved longitudinally from one end.

In Figure 6 is illustrated a modified form of my invention in which the nipple 17 extends into ducts or passageway 31 through 30 the teeth 6 which ducts open at 32 adjacent the ends of the teeth, for distributing liquid not on the surface of the hair being combed but on the scalp. Such a construction as shown in Figure 6 may be more satisfactory 35 when utilized for the purpose of applying medications to the scalp, whereas the form shown in Figure 4 in which the nipples 17 extend through the apertures 35 between the teeth, is preferable for the purpose of applying 40 moisture to the surface of the hair simply for the purpose of facilitating the combing of the hair.

In the operation of my invention, it is often desired by the person using the comb that the 45 comb be entirely dry at one end and have means for dispensing moisture at the other end. In such case, the operator will place one end of the comb in water or other suitable liquid with the plate 10 depressed for deflating 50 the sack 9 and upon releasing the end 13 of the lever 11 the sack will automatically assume its normal shape causing water to enter the cells 15 at one end of the sack, leaving the other cells empty. Obviously the cells 55 corresponding to the nipples which were immersed in the liquid will be the ones which will draw in the liquid. If it is desired to dispense or distribute liquid from the entire length of the column, all of the nipples 17 60 must be immersed in the water, in exactly the same manner that a fountain pen is filled.

It will be readily appreciated by those skilled in the art that the device herein illustrated and described is susceptible of various 65 modifications and changes without depart-

ing from the principles of the invention, and I desire that the patent to be granted hereon shall not be limited in any manner except as necessitated by the prior art.

I claim as my invention:

1. A fountain comb comprising a body and a plurality of longitudinally spaced teeth, said body having a longitudinal cavity therein, and apertures extending from the cavity to the spaces between the teeth, a multi-cell self-sustaining resilient sack in the cavity of the body and adapted to contain liquid to be fed to the hair being combed, and means on said sack for delivering liquid to the apertures between the teeth. 70

2. A fountain comb comprising a body and a plurality of longitudinally spaced teeth, said body having a longitudinal cavity therein, and apertures extending from the cavity to the surface of the teeth, a self-sustaining resilient sack in the cavity adapted to contain liquid to be fed to the teeth of the comb, and a plurality of longitudinally spaced nipples on said sack disposed in the apertures for 75 feeding liquid therethrough. 80

3. A fountain comb comprising a body and a plurality of longitudinally spaced teeth, said body having a longitudinal cavity therein, and apertures extending from the cavity to the surface of the teeth, a self-sustaining resilient sack in the cavity adapted to contain liquid to be fed to the teeth of the comb, and a plurality of longitudinally spaced nipples on said sack disposed in the apertures for 85 feeding liquid therethrough, said sack comprising a plurality of longitudinally arranged cells, the interiors of which are hermetically sealed from each other. 90

4. A fountain comb comprising a body and a plurality of longitudinally spaced teeth, said body having a longitudinal cavity therein, and apertures extending from the cavity to the surface of the teeth, a self-sustaining resilient sack in the cavity adapted to contain liquid to be fed to the teeth of the comb, a plurality of longitudinally spaced nipples on 100 said sack disposed in the apertures for feeding liquid therethrough, said sack comprising a plurality of longitudinally arranged cells, the interiors of which are hermetically sealed from each other, and means for deflating said 105 sack to permit refilling of the cells with liquid. 110

5. A fountain comb comprising a body and a plurality of longitudinally spaced teeth, said body having a longitudinal cavity therein, and apertures extending from the cavity to the surface of the teeth, a self-sustaining resilient sack in the cavity adapted to contain liquid to be fed to the teeth of the comb, a plurality of longitudinally spaced nipples on 115 said sack disposed in the apertures for feeding liquid therethrough, and means for deflating said sack to permit the same to be 120 refilled with liquid. 125

6. A fountain comb comprising teeth and 130

- a hollow substantially cylindrical body, a multi-cell rubber sack snugly fitted in said hollow body, said sack including a plurality of depending nipples, said comb having a plurality of apertures corresponding to said nipples and opening adjacent the upper ends of the teeth for automatically distributing fluid from said sack upon the hair when being combed. 5
7. A fountain comb comprising teeth and a hollow substantially cylindrical body, a multi-cell rubber sack snugly fitted in said hollow body, said sack including a plurality of depending nipples, said comb having a plurality of apertures corresponding to said nipples and opening adjacent the upper ends of the teeth for automatically distributing fluid from said sack upon the hair when being combed, and means for collapsing said sack in preparation to drawing liquid into the cells. 10
8. As an article of manufacture, a self-sustaining collapsible rubber sack for containing and distributing liquid, said sack comprising a plurality of longitudinally arranged cells, the interiors of which are hermetically sealed from adjacent cells, and means on said sack through which liquid may be distributed and replenished. 15
9. As an article of manufacture, a self-sustaining collapsible rubber sack for containing and distributing liquid, said sack comprising a plurality of longitudinally arranged cells, the interiors of which are hermetically sealed from adjacent cells, and a plurality of depending nipples longitudinally spaced along one side, said nipples having substantially capillary openings, there being at least one nipple to a cell through which liquid may be distributed and replenished. 20
10. As an article of manufacture, a feed sack for a fountain comb, consisting of a single normally self-sustaining collapsible rubber tube closed at both ends, the sides of said tube permanently and hermetically sealed together at longitudinally spaced intervals, thereby providing a plurality of cells adapted to contain a liquid, and means on said sack through which liquid may be distributed from said cells and replenished thereto. 25
11. As an article of manufacture, a feed sack for a fountain comb, consisting of a single normally self-sustaining collapsible rubber tube closed at both ends, the sides of said tube being permanently and hermetically sealed together at longitudinally spaced intervals in a single vertical plane providing vertical stiffening partitions for resisting collapsing of the sack, and means on said sack at points between said partitions for distributing liquid from said sack. 30
12. As an article of manufacture, a feed sack for a fountain comb, consisting of a single normally self-sustaining collapsible rubber tube closed at both ends, the sides of said tube being permanently and hermetically sealed together at longitudinally spaced intervals in a single vertical plane providing vertical stiffening partitions for resisting collapsing of the sack, and means on said sack at points between said partitions for distributing liquid from said sack. 35
13. A fountain comb comprising a plurality of longitudinally spaced teeth, a body supporting said teeth, and having a relatively large cavity extending longitudinally of the comb, said body having apertures leading from the cavity to spaces between the teeth, a rubber sack for containing liquid fitted in the cavity and including a plurality of nipples disposed in the apertures and extending below the upper ends of the teeth for engaging hair and distributing liquid directly thereto when the comb is in use. 40
14. A fountain comb comprising a plurality of longitudinally spaced teeth, a body supporting said teeth, and having a relatively large cavity extending longitudinally of the comb, said body having apertures leading from the cavity to spaces between the teeth, a rubber sack for containing liquid fitted in the cavity and including a plurality of nipples disposed in the apertures and extending below the upper ends of the teeth for engaging hair and distributing liquid directly thereto when the comb is in use, said sack including a plurality of vertically disposed partitions adapted to increase the vertical rigidity of the sack and means for deflating said sack in preparation for refilling the same through said nipples. 45
15. A fountain comb comprising a plurality of longitudinally spaced teeth, a body supporting said teeth, and having a relatively large cavity extending longitudinally of the comb, said body having apertures leading from the cavity to spaces between the teeth, a rubber sack for containing liquid fitted in the cavity and including a plurality of nipples disposed in the apertures and extending below the upper ends of the teeth for engaging hair and distributing liquid directly thereto when the comb is in use, said sack including a plurality of partitions disposed in a single plane for dividing said sack into a plurality of longitudinally arranged cells, said nipples being disposed such that at least one communicates with each cell. 50
16. A fountain comb comprising a plurality of longitudinally spaced teeth, a body supporting said teeth, and having a relatively large cavity extending longitudinally of the comb, said body having apertures leading from the cavity to spaces between the teeth, a rubber sack for containing liquid fitted in the cavity and including a plurality of partitions disposed in a single plane for dividing said sack into a plurality of longitudinally arranged cells, said nipples being disposed such that at least one communicates with each cell. 55

- of nipples disposed in the apertures and extending below the upper ends of the teeth for engaging hair and distributing liquid directly thereto when the comb is in use,
- 5 said sack including a plurality of partitions disposed in a single plane for increasing the rigidity of the sack in that plane, and means disposed in a plane normal to the plane of said partitions adapted to be urged against said sack to deflate the same.
- 10 17. A fountain comb comprising a body and a plurality of longitudinally spaced teeth, said body having a longitudinal cavity therein, and apertures extending from the
- 15 cavity to the surface of the teeth, a self-sustaining resilient sack in the cavity adapted to contain liquid to be fed to the teeth of the comb, and a plurality of longitudinally spaced nipples on said sack disposed in the
- 20 apertures for feeding liquid therethrough, said comb having a longitudinal groove adjacent the upper end of the teeth and a shield adapted to fit over said teeth and including a portion for engaging in the groove on the
- 25 comb to hold the shield in position against accidental displacement.

In testimony whereof I have herunto subscribed my name at Chicago, Cook County, Illinois.
